(57) **CLAIM**

The ornamental design for a face mask, as shown and described.

DESCRIPTION

FIG. 1 is an elevational view from the right side, the left side being a mirror image thereof;

FIG. 2 is a top plan view thereof;

FIG. 3 is a bottom plan view thereof;

FIG. 4 is a front elevational view wherein, for example, a filter may cover the air holes externally; and,

FIG. 5 is a rear elevational view wherein, for example, a filter may cover the air holes internally.
The broken lines in the drawings show portions of the face mask and form no part of the claimed design.
